UNITED STATES PATENT OFFICE.

RICHARD T. NEWTON, OF NUTLEY, NEW JERSEY.

AUTOMOBILE-BUFFER.

1,257,380.

Specification of Letters Patent. Patented Feb. 26, 1918.

Application filed March 4, 1915. Serial No. 12,038.

To all whom it may concern:

Be it known that I, RICHARD T. NEWTON, a citizen of the United States of America, and residing in the city of Nutley, in the county of Essex and State of New Jersey, have invented a certain new and Improved Automobile-Buffer, of which the following is a specification.

My invention relates to automobile buffers and the object of my invention is to provide a simple and rugged device of this character which may be readily mounted on automobile frames of various sizes and types without injury thereto.

15 In the accompanying drawings,

Figure 1 is a side elevation of a buffer support in which my invention is illustratively embodied;

Fig. 2 is a partial plan thereof;

20 Fig. 3 is a perspective of a buffer installation embodying the invention;

Fig. 4 is a side elevation of a further modification;

Fig. 5 is a plan of the latter with the buffer spring removed;

Fig. 6 is a side elevation of a further modification; and

Fig. 7 is a perspective of the detachable abutment shown in Figs. 4-5.

30 Fig. 8 is a plan view of the bumper carrying end of the supporting lever, the lower flange of the bumper being also partially shown.

In the form shown in Figs. 1 and 2 the buffer 10 is of channel section and is secured to the heads of a pair of supporting arms 11, each of which respectively is pivoted at 12 to its base 13 which in turn is held by means of yokes 14 upon the usual forward extensions 15 of the longitudinal members of the chassis. The head of each arm is slotted at 16 to form a pair of expansion jaws 17 between which works an expansion bolt 18. The outer face of each jaw is channeled at 19 to receive one of the ribs 20 riveted to the opposite sides of the channel 10 and extending a few inches longitudinally of the buffer to permit the adjustment of the buffer supports to various widths of chassis. A flat 21 with nipple 22 forms a seat for one end of the compression spring 23, the other end of which bears against the inclined abutment 24 cast, with its nipple 25 and supporting flange 26, in one with the base 13. Side lugs 27 on the arm 11 form stops which bear against the edges of the

cheeks 28 through which the pivot pin 12 passes. The spring 23 is put in under heavy pressure, so that the stops are firmly pressed against the cheeks 28 and the buffer maintained with comparative rigidity in its normal position.

When the buffer is displaced the supporting arm 11 swings back upon its pivot 12 compressing the spring 23 and thus cushioning the shock to which the buffer is subjected. The stops 27 simultaneously move away from the cheeks 28, engaging them again however when the spring 23 expands, thus returning the buffer to normal position. This construction is simple and rugged and well fitted for the service demanded. The arc through which the arm 11 is displaced on the compression of the spring is relatively small and the thrust is always substantially at right angles to the face of the abutment 24 so that there is no danger of the spring "jumping" the nipples 22 or 24 even though the latter be comparatively short.

80 An obvious modification is shown in Fig. 6 in which the abutment 29 is slotted at 30 to permit the passage therethrough of the spindle 31 fast with the arm 11 and on which the spring is coiled. The cross pin 32 passed through the spindle 31 behind the abutment bears normally against the back of the latter and takes the place of the stops 27 which may in this case be omitted.

85 The further modification shown in Figs. 4 and 5, has certain features of adjustability which enable the buffer to be fitted to the frame the forward extensions 15 of which have different degrees of inclination. Different means for fastening the head of the arm 110 to the buffer bar 10 are also provided. In this construction the head comprises a lower jaw 33 of considerably greater width than the arm 110 and slotted at 34 to permit the passage of the securing bolt 35 therethrough and through the hole 36 drilled in the lower side of the channel 10, beneath which the nut 37 is screwed onto the shank of the bolt. This construction permits the bolt to be passed through the slot 34 and hole 36 while the latter is at one side of the plane of the arm 110 whereupon the buffer channel 10 is moved laterally until the bolt head 38 lies in the space 39 between the lower jaw 33 and the upper jaw 40 of the head. The nut 37 is then tightened to rigidly unite the parts. The upper

jaw 40 in this case plays no part in the fastening, but forms merely a thrust member, the outer faces of the two jaws lying in the same plane and bearing against the vertical inner face of the channel 10.

If the hole 36 happens through error to be drilled at one side of the plane of the arm 110, the bolt 35 may be fastened in this position, since it is not essential, though preferable, that it lie in the plane of the supporting arm.

The base 130 is as before provided with checks 28 through which passes the pivot pin 12 on which the arm 110 is pivoted. Since 15 the base may lie at different inclination on different frames 14, while at the same time it is desirable that the buffer should present its face A vertical, it is preferable to provide an adjustable stop by means of which the 20 proper normal position of the buffer may be maintained. A simple means for accomplishing this is here shown, comprising a stop screw 41 threaded through a tapped shoulder 42 in the base and bearing at its 25 lower end against a shoulder 43 formed in the lower end of the supporting arm 110 at the base of a slot 44. By turning the screw 41 down or up as may be necessary, the position of the arm 110 may be adjusted as 30 may be necessary to bring the face A of the buffer into a vertical plane.

This adjustment of the arm 110 may result in throwing the seat 21 out of alignment with the seat 45 on the base. To meet this 35 difficulty, this seat 45 is made as an independent member provided with a foot-piece 46 engaging in a well 47 formed in the base. The forward side of this well is undercut at 48 to receive the wedge-shaped toe 49 of the 40 foot piece. The constant pressure of the spring holds the seat in position on the base, the backward thrust being met at 50 while the upward-tilting effort at the toe 49 is taken up by the overhang 48 of the side of the 45 well at this point. If a stock of seats 45 be made having different inclinations to the base, it is possible to replace one by another having its bearing face parallel to the face of the seat 21 on the supporting 50 arm.

In this modification I have also obviated the use of one of the holding yokes by extending the forward end of the base downward in the form of a hook 51 which engages 55 the end of the chassis extension. The single yoke 52 which is provided, is in reversed position from that shown in Fig. 1 and the legs extend upward from beneath the chassis through holes in bosses 53 at the side of the 60 base.

Various other modifications will readily suggest themselves without departing from what I claim as my invention.

I claim as my invention:—

65 1. An automobile buffer comprising a

buffer bar, a one-piece supporting arm engaging the same, a base plate adapted to lie against and be rigidly mounted on the chassis and having a boss at its forward end to which said supporting arm is directly and 70 pivotally connected, an abutment on said base to the rear of said boss and a compression spring extending between said abutment and supporting arm, for the purpose described.

2. An automobile buffer comprising a buffer bar, a supporting arm engaging the same, a base adapted to be rigidly mounted on the chassis and having a boss at its forward end to which said supporting arm is 80 pivotally connected, an abutment on said base to the rear of said boss and a compression spring extending between said abutment and supporting arm, together with a stop offset on said arm engaging a base 85 member to limit the forward movement of the arm under the action of said compression spring.

3. An automobile buffer comprising a buffer bar, a one-piece supporting arm engaging the same, a base plate lying against and rigidly secured to the chassis and having at its forward end a boss to which said supporting arm is directly pivoted, abutments on said base and supporting arm respectively and lying on opposite sides of the point at which said arm is pivoted to the base, and a compression spring extending between and seated under tension against said abutments, said supporting arm swinging 100 on its pivot on the displacement of the buffer to compress the buffer spring.

4. An automobile buffer comprising a buffer bar, a one-piece supporting arm engaging the same, a base plate lying against and 105 rigidly secured to the chassis and having at its forward end a boss to which said supporting arm is directly pivoted, abutments on said arm and base lying in a substantially horizontal plane above and at substantially 110 equal distances on opposite sides of a vertical plane passing through the pivoting point of the buffer supporting arm, together with a compression spring extending between said abutments for the purpose described.

5. An automobile buffer comprising a buffer bar, a supporting arm engaging the same, a base on which said arm is pivoted, an upstanding abutment carried by the base 120 to the rear of the point of attachment of the supporting arm, and a compression spring extending under tension between said abutment and the supporting arm together with a stop offset on said arm engaging a base 125 member to limit the forward movement of the arm under the action of said compression spring, for the purpose described.

6. An automobile buffer comprising a buffer bar, a supporting arm engaging the 130

same, a base on which the latter is pivoted and having an undercut recess, a detachable spring abutment having a foot fitting in adjusted position in said undercut recess, and

6 a buffer spring extending between said abutment and supporting arm and tending through its effort to maintain the foot of the abutment within the recess.

7. An automobile buffer comprising a buffer bar, a supporting arm engaging the same, a base on which the latter is pivoted, a buffer spring extending between said base

and arm, a stop screw threaded in said base and a shoulder on said arm engaged thereby whereby the normal position of said buffer 15 may be adjustably regulated.

In testimony whereof I have signed my name to this specification, in the presence of two subscribing witnesses.
